GEORGE B. FOWLE, OF CAMBRIDGE, MASSACHUSETTS.

Design No. 4,921, dated May 23, 1871.

DESIGN FOR ORNAMENTATION OF THE BOTTOMS OF DRINKING-GLASSES.

The Schedule referred to in these Letters Patent and making part of the same.

To all whom it may concern:

Be it known that I, GEORGE B. FOWLE, of Cambridge, in the county of Middlesex and State of Massachusetts, have invented or produced a Design for Glass Tumblers, &c.; and I do hereby declare that the following, taken in connection with the drawing which accompanies and forms part of this specification, is a description of my invention sufficient to enable those skilled in the art to produce it.

My invention or design relates to the ornamentation of the bottoms of glass tumblers and other glass drinking-vessels, such ornamentation having generally some emblematic reference.

The design consists of a bird formed in the bottom of the glass.

The drawing represents a tumbler or glass beer-mug with such a device or design formed in its bottom.

a denotes the body of the tumbler;

b, the bottom; and

c, the center piece or figure constituting the design.

I claim—

The design for the ornamentation of the bottom of a drinking-vessel, substantially as described and shown.
